UNITED STATES PATENT OFFICE.

FREDERICK GEORGE CHAMBERLIN, OF FAITH, NORFOLK, ENGLAND.

DESIGN FOR A LEGGING.

54,896.

Specification for Design.

Patented Apr. 20, 1920.

Application filed September 26, 1919. Serial No. 326,684. Term of patent 14 years.

To all whom it may concern:

Be it known that I, FREDERICK GEORGE CHAMBERLIN, a subject of the King of England, and residing at The Moyse, Horsham St. Faith, Norfolk, England, have invented a new, original, and ornamental Design for a Legging, of which the following is a specification, reference being had to the accompanying drawing, forming part thereof, wherein—

Fig. 2 is a like view showing the legging buckled in its closed position of use, and

Fig. 3 is a rear perspective view of the legging showing the vertical slit in its bottom margin opened, all of which figures illustrate my new design.

I claim:

The ornamental design for a legging, as shown.

FREDERICK GEORGE CHAMBERLIN.
